PAGE 2

To all whom it may concern:

Be it known that I, Bernard Tebb, a British subject, citizen of the United Kingdom and Colonies, of 701 Marfleet Lane, Hull, Yorkshire, England, have invented a new, original, and ornamental Design for a Tool for Inserting Wire Hook Fasteners in Power Transmission Belts, of which the following is a specification, reference being had to the accompanying drawings, forming part thereof, in which:

Figure 1 is a perspective view showing the front, top and one side of a tool for inserting wire hook fasteners in power transmission belts, embodying my new design; and

Figure 2 is a perspective view showing the rear, bottom and other side thereof.

I claim:

The ornamental design for a tool for inserting wire hook fasteners in power transmission belts, substantially as shown.
